(No Model.)

D. P. MORGAN.

WATER MOTOR.

No. 269,696.

Patented Dec. 26, 1882.

UNITED STATES PATENT OFFICE.

DANIEL P. MORGAN, OF FITCHBURG, MASSACHUSETTS, ASSIGNOR TO
CHARLES A. SAWYER, OF SAME PLACE.

WATER-MOTOR.

SPECIFICATION forming part of Letters Patent No. 269,696, dated December 26, 1882.

Application filed July 10, 1882. (No model.)

To all whom it may concern:

Be it known that I, DANIEL P. MORGAN, of Fitchburg, in the county of Worcester and State of Massachusetts, have invented a new and Improved Water-Motor; and I hereby declare the following to be a full, clear, and exact description thereof, reference being had to the accompanying drawings, making part of this specification, in which—

- 10 Figure 1 is a plan of the motor with the plate of the casing removed. Fig. 2 is a vertical section on the line x x of Fig. 1. Fig. 3 is a detail view of the bucket. Fig. 4 is a detail view of the nozzle.
- 15 My invention relates to that class of water-motors designed to operate sewing-machines and other light machinery, and has for its object to provide a cheap and durable motor which is readily reversible.
- 20 My invention consists, first, in the peculiar construction of the buckets of the motor-wheel; secondly, in a novel construction of nozzle; thirdly, in a casing provided with duplex openings for a nozzle, combined with a reversible wheel; and, fourth, in a disk secured to the driving-shaft between the motor-wheel and the casing, the action of which prevents leakage, all of which will hereinafter be specifically described.
- 25 In order that those skilled in the art may make and use my invention, I will proceed to describe the manner in which I have carried it out.

In the said drawings, A is the casing or housing, provided with the relief-pocket a and waste-pipe a' . A spindle, b , passes through the casing, and has on its outer end a driving-pulley and on its inner end a power-wheel, B, composed of a central hub or disk, b' , from which radiate equidistant spokes or arms b'' , bearing on their ends buckets C to receive the impact of the entering stream of water. The buckets are made of short tubes, with one end open, as seen at i , and a portion of the tube cut away, as seen at 1, 2, 3, and 4. This construction prevents the water from rebounding toward the sides of the casing when it strikes the tubular buckets through the cut-away portion 1 2 3 4.

The nozzle D enters the casing at the upper 50 edge, so that the water will strike the buckets in a line tangential to the line of their travel. The nozzle connected with the inlet-pipe consists of a short pipe, e , into the discharge end of which is secured a double conical plug, e' , 55 provided with a central longitudinal hole of much less diameter than that of pipe e . This form of nozzle I find highly efficient, as the centrally-perforated conical plug e' cuts out, so to speak, a small stream from the center of 60 the main stream, where the water has the greatest velocity.

On the opposite side of the casing from nozzle D is an opening, E, properly tapped, and of a proper size to receive said nozzle, but 65 closed with a screw-plug, F. By this construction the motor can be made to run in either direction without changing the position of the casing by simply reversing the wheel—that is, by taking the wheel off the spindle, 70 turning it, and replacing it, so the open face of the buckets are toward opening E, and changing the nozzle to opening E and transferring the screw-plug. This construction of wheel, as described, tends to throw the water 75 toward the edge of the casing; but in order to prevent any water working out through the journal-bearing I secure to the spindle b , close to the end of the journal-box, a disk, H, which turns at a high velocity with said spindle, and 80 as any water approaches the bearing it comes in contact with disk H and is thrown away from the center by the centrifugal force generated by the revolving disk.

I am aware that heretofore turbine wheels 85 have been made wherein two fixed water-conduits have been connected with the casing and adapted to operate alternately against the sides of a star-shaped wheel. Hence I make no broad claim to devices adapted to alternately 90 impinge a stream of water on the opposite sides of a water-wheel.

Having thus described my invention, what I claim as new, and desire to secure by Letters Patent, is—

1. The bucket C, made of an open-end cylinder having the portion 1 2 3 4 cut away, substantially as set forth.

2. The nozzle consisting of the pipe e , in combination with the inserted double conical perforated plug e' , substantially as specified.
3. In a water-motor, a casing, A, provided with duplex nozzle-taps, in combination with a reversible motor-wheel, substantially as described.
4. The disk H, in combination with and secured to spindle b against the end of the journal-box, and adapted to throw off the water from the journal, substantially as set forth.

DANIEL PHILIP MORGAN.
